AUTOMOBILE DOOR HANDLE

Alex Kraus, Los Angeles, Calif.
(1650 W. Rosecrans Ave., Gardena, Calif. 90249)

Filed Apr. 7, 1969, Ser. No. 16,608

Term of patent 14 years

Int. Cl. D8—03

U.S. Cl. D8—161

FIG. 1.

FIG. 2.

FIG. 3.

FIG. 4.

FIGURE 1 is a front view of the automobile door handle;

FIGURE 2 is a side elevation of the automobile door handle;

FIGURE 3 is a rear view of the automobile door handle; and

FIGURE 4 is an end view of the automobile door handle rotated 90° from the side elevational view of FIG. 2.

I claim:

The ornamental design for an automobile door handle, as shown.
